Primary Examiner — W. A. Teddy Falloway

(57) **CLAIM**

The ornamental design for a set of pots, as shown and described.

DESCRIPTION

Figure 1.1 is a perspective view of a set of pots of a first embodiment;

Figure 1.2 is a back view of a set of pots of a first embodiment;

Figure 1.3 is a bottom view of a set of pots of a first embodiment;

Figure 1.4 is a front view of a set of pots of a first embodiment;

Figure 1.5 is a side view of a set of pots of a first embodiment;

Figure 1.6 is a top view of a set of pots of a first embodiment;

Figure 2.1 is a perspective view of a set of pots of a second embodiment;

Figure 2.2 is a back view of a set of pots of a second embodiment;

Figure 2.3 is a bottom view of a set of pots of a second embodiment;

Figure 2.4 is a front view of a set of pots of a second embodiment;

Figure 2.5 is a side view of a set of pots of a second embodiment;

Figure 2.6 is a top view of a set of pots of a second embodiment;

Figure 3.1 is a perspective view of a set of pots of a third embodiment;

Figure 3.2 is a back view of a set of pots of a third embodiment;

Figure 3.3 is a bottom view of a set of pots of a third embodiment;

Figure 3.4 is a front view of a set of pots of a third embodiment;

Figure 3.5 is a side view of a set of pots of a third embodiment;

Figure 3.6 is a top view of a set of pots of a third embodiment;

Figure 4.1 is a perspective view of a set of pots of a fourth embodiment;

(Continued)

Figure 4.2 is a back view of a set of pots of a fourth embodiment;
 Figure 4.3 is a bottom view of a set of pots of a fourth embodiment;
 Figure 4.4 is a front view of a set of pots of a fourth embodiment;
 Figure 4.5 is a left-side view of a set of pots of a fourth embodiment;
 Figure 4.6 is a right-side view of a set of pots of a fourth embodiment;
 Figure 4.7 is a top view of a set of pots of a fourth embodiment.
 The broken lines illustrate portions of the set of pots and form no part of the claimed design.

1 Claim, 25 Drawing Sheets
